TOOL FOR APPLYING SHEET CLAMPS

John C. Wright, Los Angeles, Calif., assignor, by
mesne assignments, to Herman H. Helbush, Los
Angeles, Calif.

Application June 19, 1943, Serial No. 491,458

1 Claim. (Cl. 29—270)

1
This invention relates to tools for installing or applying clamps to sheet parts and the like to temporarily hold such parts against movement preparatory to and during riveting, spot welding, and like operations.

Spring actuated sheet clamps or fasteners are in extensive use to temporarily hold sheet parts against relative movement during the riveting, welding and bolting together of the sheets. Clamps of the general character herein referred are disclosed in Patent Number 2,317,315 granted to F. C. Wallace April 20, 1943. Tools resembling pliers have been employed to compress the clamps and facilitate their insertion into the registering openings in the sheet parts. Frequently the partly compressed clamps escape from the plier-like tools. The clamps when thus accidentally released from the tools are projected by the force of their springs with sufficient velocity to injure the operator and adjacent workmen.

It is a general object of this invention to provide a practical and effective tool for applying sheet clamps that is safe and dependable in operation. The partially compressed clamps cannot escape from the tool of the invention to injure the operator or other workmen.

Another object of the invention is to provide a tool of the character referred to embodying chuck elements or cradles that are adapted to close about the shell or shank of the clamp to positively prevent the escape of the clamp when the latter is compressed.

Another object of this invention is to provide a tool of the character mentioned in which the cradles are automatically opened and closed simultaneously with the retraction and actuation of the clamp compressing plunger.

A further object of the invention is to provide a tool of the character referred to that is easy and convenient to operate and simple and inexpensive to manufacture.

The various objects and features of the invention will be fully understood from the following detailed description of typical preferred forms of the invention throughout which description reference is made to the accompanying drawing in which:

Fig. 1 is a central longitudinal detailed sectional view of the tool of the invention.

Fig. 2 is a front elevation of the tool.

Fig. 3 is a horizontal detailed sectional view taken as indicated by line 3—3 on Fig. 1.

Fig. 4 is a fragmentary detailed sectional view taken as indicated by line 4—4 on Fig. 1, and

2
Fig. 5 is a fragmentary vertical sectional view of another embodiment of the invention.

The form of the invention illustrated in Figures 1 to 4 inclusive may be said to comprise generally a body 10, a reciprocable plunger 11 in the body, means 12 for operating the plunger 11, one or more holding members or cradles 13 for holding the shank of a clamp in alignment with the plunger 11, and means 14 for operating the cradles.

The housing or body 10 is preferably, though not necessarily, of pistol shape to make the tool convenient to operate. The construction of the body 10 may vary greatly. In the case illustrated 15 the body 10 comprises two complementary sections 15 shaped or pressed to constitute a hollow housing. The sections 15 have indented parts 16 spot welded together at 16a so that the two sections form a rigid unit. Two of these indented 20 parts 16b are elongated horizontally and are spaced apart vertically to serve as guides for the plunger 11 as will be later described. The body 10 constructed as just described has a handle grip 17 and a barrel 18. The barrel 18 houses the plunger 11 and is open at its forward end to permit the plunger to act on the sheet clamps.

The plunger 11 is an elongated part operable to press against the head of the sheet clamp to compress the clamp. In practice the plunger 11 30 may be square or rectangular in cross section and is guided for movement toward and away from the open forward end of the barrel 18. The above mentioned indented parts 16b may serve as guides for the rear portion of the plunger and the side walls of the barrel aid in guiding the plunger. A cylindrical portion 20 is provided on the forward end of the plunger 11 to engage the clamp and the forward end face of the plunger 35 may have a recess or dimple for cooperating with the rounded end of the clamp.

The means 12 for operating the plunger 11 includes a handle or trigger 21 to be operated by the workman to actuate the plunger 11. The trigger 21 extends downwardly in front of the 45 handle 17 and its upper portion enters an opening 22 in the forward edge of the body 10. A horizontal pivot pin 23 supports the trigger 21 for pivotal movement. As illustrated, the trigger 21 may be a channel shaped part and the pivot 50 pin 23 may pass through openings in the spaced side parts of the trigger and may have its ends supported in the side walls of the body, see Fig. 4. The trigger 21 is shaped and positioned to be conveniently operated by the fingers of the workman's hand which grips the handle 17. A notch

24 is provided in the lower edge of the plunger 11 and a finger 25 is provided on the upper end of the trigger 21 to engage in notch 24. It will be seen that upon rearward movement of the trigger 21 the finger 25 engaging in the notch 24 produces forward movement of the plunger 11.

The means 12 for operating the plunger 11 further includes a helical tension spring 26 for reTRACTING the plunger 11 following operation. An ear 27 is provided on the trigger 21 within the body 10 and a similar ear 28 is provided on the interior of the handle 17. The spring 26 is connected under tension between the ears 27 and 28. It will be seen that the tension spring 26 normally holds the plunger 11 in a reTRACTed position and holds the trigger 21 in the forward position indicated by the broken lines in Fig. 1. The rear end of the plunger 11 may contact the rear wall of the barrel 18 to limit rearward movement of the plunger.

The members 13 are provided to enclose and retain the shell or shank of the clamp when the clamp is compressed. In accordance with the invention there may be one or more members 13. In the particular embodiment of the invention being described there are two like and opposed members 13 entering the forward end of the barrel 18. The members 13 are supported for pivotal movement by vertically spaced horizontal pivot pins 30. The members 13 project forwardly beyond the end of the barrel 18 and the end portion of the barrel has notches 31 to permit substantial outward swinging of the members. As best illustrated in Fig. 2, the forward portions of the members 13 are tubular and are generally square in transverse cross section.

The opposing surfaces 32 of the members 13 are designed to effectively engage and hold the clamp. These surfaces 32 are cylindrically curved and each has a curvature of slightly less than 180° so that when the members 13 are in their closed active positions the shank of the clamp is substantially entirely surrounded. The active concave surfaces 32 of the members 13 are reduced in diameter adjacent the forward ends of the members to provide the members with abrupt rearwardly facing shoulders 33. The shoulders 33 are engageable with the usual flange on the rear end of the clamp shank. When the members 13 are closed about the clamp, the clamp is securely and positively held against displacement.

The means 14 for operating the cradle members 13 serves to open or spread the members when the plunger is moved rearwardly and serves to swing the members inwardly about the clamp when the plunger is moved forwardly. The means 14 includes tail-pieces 34 on the cradle members 13. The tail-pieces 34 have rounded convex extremities. The means 14 further includes projections or cams 35 on the upper and lower sides of the plunger 11 for cooperating with tail-pieces 34. When the plunger 11 is moved forwardly the cams 35 simultaneously engage the rounded ends of the tail-pieces 34 to swing the members 13 inwardly or toward one another to engage about the clamp.

The operating means 14 further includes springs 37 and 38. These springs are housed within the barrel 11 and are in the form of leaf springs. The spring 37 is engaged or hooked behind the upper part 16b and bears downwardly against a pin 39 on the tail-piece 34 of the upper member 13 to urge the upper member outwardly or upwardly. The spring 38 is hooked around

the pivot pin 23 and bears upwardly against a pin 40 on the tail-piece 34 of the lower member 13 to urge the lower member outwardly or downwardly. When the plunger 11 is restored to its normal or idle position the springs 37 and 38 automatically spread the members 13 to their open position so that the tool may readily receive the next clamp. In this connection it will be noted that in the locations at which the tail-pieces join the cradles 13 arcuate enlargements are provided which cooperate with the upper and lower sides of the plunger 11 to guide the latter while being extended and reTRACTed in the manner described. It will be noted further that the curved surfaces of the enlargements are coaxial with relation to the axes of the respective pins 30 and as a consequence the enlargements will cooperate with the plunger to guide the outer end of the latter in the desired relation with respect to the operating elements of the clamps while at the same time enabling rocking movements of the cradles in the manner and for the purpose described without impairing the guiding action of the enlargements.

25 The embodiment of the invention illustrated in Fig. 5 includes a single pivoted guard or cradle member 13a. The member 13a may be of the same construction as the members 13 and is pivotally secured to the forward portion of the barrel 18 by a pivot pin 30a. The upper guard or cradle 13b may be fixed in the said portion of the barrel 18 as by welding or the like, or may be formed as an integral part of the body 10 as illustrated. The members 13a and 13b have opposing cylindrically curved concave surfaces 32a shaped to conform to the body of the clamp and have abrupt inwardly facing shoulders 33a for engaging with the flange of the clamp.

The pivoted guard or cradle member 13a has 40 a tail-piece 51 extending rearwardly in the barrel 18 and the underside of the plunger 11 has a downwardly projecting cam 52 for cooperating with the rounded end of the tail-piece 51. Upon forward movement of the plunger 11 the cam 52 cooperates with the rounded end of the tail-piece 51 to swing the member 13a upwardly to its active position to engage about the shank of the clamp. A spring 38a engages upwardly against a pin 40a on the tail-piece 51 to normally urge the member 13a to its down or open position.

55 In this form of the invention a notch 53 is formed in the underside of the plunger 11 in front of the cam 52 to permit ample pivotal movement of the member 13a. The broken lines in Fig. 5 illustrate the manner in which the tail-piece 51 enters the notch 53 when the member 13a is in its reTRACTed position. The parts are formed and proportioned so that the sheet clamp may be readily entered between the fixed member 13b and the pivoted member 13a when the member 13a is in its open position.

60 It is believed that the operation of the tool will be readily understood from the foregoing detailed description. Referring now to the form of the invention illustrated in Figures 1 to 4 inclusive, it will be apparent that the sheet clamp may be easily engaged in the forward end of the tool when the members 13 are in the open positions illustrated by the broken lines in Fig. 1. When it is desired to compress the clamp the trigger 21 is pivoted rearwardly. This causes forward movement of the plunger 11 and as the plunger moves forwardly the cams 35 cooperate 70 with the tail-pieces 34 to pivot the members 13

inwardly toward one another. Thus the guard members or cradle members 13 are actuated to engage about the shank of the clamp when the clamp is to be compressed. The members 13 engaging about the clamp positively preclude the possibility of the clamp springing or escaping from the tool and thus eliminate all hazard in the use of the tool. When the pressure is relieved from the trigger 21 the spring 26 restores the plunger 11 and the trigger 21 to their normal positions. Upon restoration of the plunger 11 the members 13 are swung to open or idle positions by the springs 37 and 38.

Having described only typical forms of the invention I do not wish to be limited to the specific details herein set forth, but wish to reserve to myself any variations or modifications that may appear to those skilled in the art or fall within the scope of the following claim.

I claim:

A tool for applying clamps of the kind having a shank and a movable operating element, said tool including a body, a barrel on said body having an open end, a plunger in said barrel having an outer end which is engageable with the movable operating elements of said clamps, a lever for moving said plunger axially in said barrel toward the open end thereof, resilient means for restoring said plunger to, and for normally holding it in a retracted position, outwardly extending cam surfaces provided on opposite sides of said plunger a substantial distance inwardly from the outer end thereof, a pair of cooperating cradles, said cradles being located at opposite sides of said plunger and having tail-pieces, pins connecting said cradles to said barrel and providing pivotal mountings for said cradles, the cam surfaces on said plunger being located inwardly with respect to said tail-pieces in the retracted position of said plunger, and resilient means act-

ing on said tail-pieces to pivot said cradles on said pins and in so doing spread them apart so that a clamp may be arranged between them when the plunger is so retracted, said cams being operative when said lever is actuated and said plunger is extended, and prior to engagement of the latter with the movable operating element of said clamp, to engage said tail-pieces and pivot the cradles on said pins to cause them to embrace the shank of said clamp, whereby during continued movement of said plunger the movable element of the clamp will be operated, and inwardly-extending, arcuate enlargements on said tail-pieces which engage and guide the outer end of said plunger, the centers of said arcuate enlargements being coincident with the axes of said pins, whereby said enlargements are caused to maintain guiding contact with said plunger as said cradles are pivoted on said pins in the manner and for the purpose described.

JOHN C. WRIGHT.
